HERMETICALLY SEALED ELECTRO-MAGNETIC RELAY

Regis R. Bohlin, Cupertino, Calif., assignor to Jennings Radio Manufacturing Corporation, San Jose, Calif., a corporation of Delaware

Filed Apr. 26, 1963, Ser. No. 74,626

Term of patent 14 years

(Cl. D26—1)

FIG. 1 is a perspective view of a hermetically sealed electromagnetic relay, showing my new design;

FIG. 2 is a perspective view of the relay as seen from the other end;

FIG. 3 is a side elevational view;

FIG. 4 is an end elevational view as seen from the top of FIG. 3; and

FIG. 5 is an end elevational view as seen from the bottom of FIG. 3.

I claim:

The ornamental design for a hermetically sealed electro-magnetic relay, as shown.
